UNITED STATES PATENT OFFICE.

SETH CURLIN, OF HICKMAN, KENTUCKY.

GARMENT-FASTENER.

1,334,230.

Specification of Letters Patent. Patented Mar. 16, 1920.

Application filed December 27, 1919. Serial No. 347,708.

To all whom it may concern:

Be it known that I, SETH CURLIN, a citizen of the United States, residing at Hickman, in the county of Fulton and State of Kentucky, have invented certain new and useful Improvements in Garment-Fasteners; and I do hereby declare the following to be a full, clear, and exact description of the invention, such as will enable others skilled in the art to which it appertains to make and use the same.

This invention relates to improvements in garment fasteners, particularly of that type forming the subject matter of my co-pending application, Serial No. 270,507, filed January 10, 1919, being an improvement thereon.

The invention has for its object, among other things, to provide for effecting an interlocking connection or action between the constituent members or elements thereof, and whereby said elements are also caused to lie with their outer surfaces or faces practically flush with each other and well inwardly, close to the garment out of inadvertent engagement or catching onto an object with which they may be brought into contact by the movement of the wearer of the garment.

A further object of the invention is to provide for casting each member of a set, constituting the fastener, the counterpart or duplicate of the other member, whereby only one die is required in casting a set, whereas two dies would otherwise be required; also by means of this arrangement the members are retained separated when applied to the garment.

A still further object of the invention is to provide a fastening simple and of the minimum number of parts and which are effective against casual separation in use.

A still further object is to provide for carrying out the above ends with facility, effectively, and expeditiously.

Further objects of the invention will be later apparent, together with the foregoing recital of objects, and will be appreciated from the following description and accompanying illustration.

The invention therefore consists of certain instrumentalities and features of construction substantially as hereinafter more fully disclosed and defined by the appended claims.

The drawing illustrates the preferred em-

bodiment or one form of my invention wherein it will be understood that various changes and modifications as relate to the detailed construction and arrangement of parts may be made without departing from the spirit or scope of my invention as covered by the claims.

In the drawing:

Figure 1 is a plan view of my fastener; 65

Fig. 2 is a vertical longitudinal section thereof;

Fig. 3 is an enlarged vertical longitudinal section of one of the members or elements of my fastener, taken centrally thereto. 70

As characteristic features of my invention or improvement, I preferably stamp up or form the members or elements 1, 1 of the fastener from light metal, preferably sheet brass, and each as the duplicate or counterpart of the other. Thus in the manufacture of my fastener, as aforesaid, I am enabled to provide for casting each of the members of a set constituting a fastener, by the use of a single die, otherwise two dies would be 80 required for that purpose. Further, by means of this arrangement the two members of the fastener are retained separated when applied to the garment.

Each of the members or elements 1, 85 which as it relates to the shank or attaching portion 2 thereof is practically the same in construction as the corresponding portion or shank as disclosed by my co-pending application herein referred to, has its other portion preferably contoured or stamped up substantially as disclosed, particularly in Fig. 1, so as to form a loop 3. The loop 3 is characterized by being provided with forwardly divergent lateral arm-like portions 90 4, which arm-like portions are flared slightly outwardly and forwardly and rounded upon their upper surfaces, their outer longitudinal edges being inclined slightly inwardly, as at 4°, the forward terminals of said arm-like portions being inclined from their outer edges inwardly and forwardly, as at 5. The arms or lateral portions 4 at their forward terminals are extended inwardly slightly, as at 6, being formed in continuation of a preferably arcuate transverse bar 8 uniting said arms, and accordingly depressed or arranged in a plane inwardly from, and out of longitudinal alinement with said arms as seen, the purpose of 105 110 which will be presently seen.

The loop 3, it will be seen where it unites

with the garment-attaching portion or shank 2, is quite narrow or contracted, forming a neck-like portion 9 and provides as the members are coupled together, for disposing or sliding the depressed *arcuate* transverse bars 8 of the two members into *engagement with the undersides of said narrow neck-like portions 9 of said members* and bringing the divergent arms 4 of said members diagonally crosswise of each other, accordingly effecting an interlocking connection or action therebetween. This arrangement also provides simultaneously for disposing particularly the interlocking portions or arms flat down compactly in place in the minimum space and so as to avoid the inadvertent catching or engagement thereof with any object which would be otherwise liable to occur by the movement of the wearer of the garment with the fastener attached thereto. It will be observed that by rounding the upper surfaces of the arm-like portions 4 of the loop 3 and slightly inclining the outer longitudinal edges thereof inwardly, as 4^a, and inclining the forward terminals of said arms inwardly and forwardly, as at 5, the lateral shifting or skewing action of the arm-like portions 4 will be restricted so as to prevent their casual or inadvertent displacement and liability of the uncoupling action of the members 1, 1.

From the foregoing it is believed that the advantages of my invention, including 35 simplicity and fewness of parts employed therein, together with the other features specially above pointed out, will be appreciated.

Having described my invention, what I 40 claim and desire to secure by Letters Patent is:

1. A fastener of the type described, in-

cluding interlocking members, each member the counterpart or duplicate of the other member and of loop formation comprising 45 divergent arm-like portions, the inner terminals of which have a constricted connection with the attaching end of the member, the outer terminals of said arm-like portions having a depressed transverse connection therebetween.

2. A fastener of the type described, including interlocking members each member being the counterpart or duplicate of the other member and of loop formation comprising 55 divergent arm-like portions, the inner terminals of which have a constricted neck-like forming connection with the attaching shank portion of the member, the outer terminals of said arm-like portions 60 having an arcuate depressed connection therebetween.

3. A fastener of the type described, including interlocking or coupling members, each member being the counterpart or duplicate 65 of the other member and of loop formation comprising divergent arm-like portions the inner terminals of which have a constricted or neck-like forming connection with the attaching shank portion of the 70 member, the outer ends of said arm-like portions being flared and inclined from their outer edges inwardly and inclined inwardly along the outer longitudinal edges thereof slightly, to restrict the lateral skewing or shifting action of the members to prevent inadvertent disengagement or uncoupling action of said members, the outer terminals of said divergent arm-like portions having an arcuate depressed transverse connection 75 therebetween.

In testimony whereof I affix my signature.

SETH CURLIN.
